TENSILE TESTING MACHINE

Walter D. Lawshe and Winston A. Gardiner,
Seattle, Wash., assignors, by mesne assignments,
to Monsanto Chemical Company, Seattle, Wash., a corporation of Delaware

Application December 27, 1944, Serial No. 569,942

9 Claims. (Cl. 73—97)

1

This invention relates to apparatus for testing the tensile strength of strips of material. While the invention is of general application the embodiment shown in the accompanying drawings and to be hereinafter described is particularly designed for testing the shear strength of the glue line between plywood plies. The main object of the invention is to provide testing apparatus of the type mentioned which is rapid and accurate in operation and yet which is of relatively simple design.

In the drawings,

Figure 1 is an isometric front view of an embodiment of the invention particularly designed for the purpose above mentioned.

Figure 2 is a plan view of the apparatus of Figure 1.

Figure 3 is a section substantially on line 3—3 of Figure 2.

Figure 4 is a section substantially on line 4—4 of Figure 3.

Figure 5 is a section substantially on line 5—5 of Figure 3.

Figure 6 shows a detail in elevation, and

Figure 7 is an elevation, partly in vertical section, of the main body of the apparatus showing the parts in a different relation from that shown in Figure 3.

Referring to the drawings, the apparatus comprises a cylindrical metal base 10 shown as fixed on a table 11 through front and rear spacing blocks 12 and 13, the body being bolted in position through a base flange 14.

The body 10 is provided with a central vertical bore 15 formed in a horizontal web 16 and a downwardly projecting flange 17 thereof. Bolted and gasketed against the lower horizontal face of flange 17 is a plate or head 18 having a central vertical opening in which is secured and welded a cylindrical member 19 having a closed lower end 20. The upper end of member 19 projects above the head 18 to provide an annular chamber 21.

Slidable in the cylinder 15 is a piston 22 having a depending shank 23 which is guided in bushings 24 and 25 which adjacent the inner wall of member 19, have vertical passages as at 26 and 27. A leather 28 is fixed to the bottom of piston 22 through a ring 29.

Threaded in an opening 30 in head 18 is a fitting 31 into which is connected a pipe 32 for conducting hydraulic pressure to the chamber 21 and the source of pressure may be the ordinary city water system as controlled by a rotary three-way valve 33, Figures 1 and 2, which is in con-

2

nnection with the supply through a pipe 34. Reference numeral 32' designates a needle valve in pipe 32 for adjusting the flow to the hydraulic chamber. Reference numeral 35 designates a vent duct formed in head 18 and member 19 which is closed by a plug 36 after water has been admitted to displace the air from cylinder 15 and member 19. It will be seen that the water pressure will act in chamber 21 and also against the bottom of shank 23, the latter action being permitted by the passages 26 and 27.

An assembly 37 comprises a plate 38 having a bottom cavity 39 rimmed by an annular shoulder against which a diaphragm 40 is clamped by means of a ring 41 which surrounds the upper reduced end of piston 22 with a close sliding fit. Plate 38 has a radial port 42 leading into chamber 39 and having threaded in its outer end a length of pipe 43 which is freely received in a lateral opening 44 of the base 10. An adapter 45 connects pipe 43 with a coil of flexible tubing 46 which extends to a pipe 47 in connection with a fitting 48 in connection with a pressure gauge 49. Also in connection with fitting 48 is an elbow 50 having an upwardly extending portion provided with a threaded closure cap 51. The described connections together with chamber 39 are filled with a suitable liquid through the elbow 50, air being vented through a radial port 52 in plate 38, the port being then closed by a plug 53. When the gauge system is filled with liquid, the diaphragm 40 is conformed to the concave top of piston 22 in the manner indicated in Figure 7. It will be observed that the piston 22 is just in contact with the diaphragm and that the piston can move upwardly relative to assembly 37 by stretching the periphery of that portion of the diaphragm which is in contact with piston 22 into the chamber 39 whose circular peripheral wall 39' has a diameter at least no smaller than that of piston 22. Such upward relative movement is transmitted by the liquid above the diaphragm to the gauge.

A plate 54 is secured to the horizontal upper edge of the base 10 and has secured thereto by a screw 55 a round bar 56, the bar being arranged on a diameter of plate 54 and being disposed above and parallel to the latter through a spacer 57. The ends of bar 56 are received in aligned bores of blocks 58 and 59 which are rigidly bolted against plate 54.

Block 58 has a bore 60 above bar 56, the axis of the bore being parallel to the axis of the bar and in the same vertical plane. A shaft 61 is rotatable in bore 60 and has an inner threaded end en-

gaged in a threaded bore of a jaw block 62 which is slidable on bar 56, the block having secured to its inner end a horizontally serrated insert 63 whose teeth are preferably downwardly directed.

Extending outwardly from block 58 is a pair of horizontally spaced parallel arms 64 and 65 which terminate in a vertical plate or head 66 between which and a plate or head 67 is clamped a cylinder 68 on the axis of shaft 61. Slidable in cylinder 68 is a piston 69 having a leather 70 clamped against its outer face through a spacer disc 71 by means of a central screw 72 which is threaded axially into a piston rod 73. A ring 74 is threaded into a central bore in head 66 and has an annular head 75 providing an inner annular edge against which bears one end of a compression spring 76 whose other end bears against piston 69. The projecting end of piston rod 73 has a circular head 77 bearing against a round head 78 on shaft 61 and coupled thereto by a swivel ring 79 which is secured to head 78 by means of a set screw 80. The cylinder and piston unit is generally designated by the reference letter C.

In the relation of parts shown in Figure 3 spring 76 has pulled the jaw block 62 into abutment with block 58 and the spacer disc 71 in cylinder 68 is just out of contact with head 67. By appropriately turning the coupling disc 79 shaft 61 can be threaded outwardly of block 62 so that spring 76 will cause disc 71 to abut head 67. Thereafter continued turning of shaft 61 in the same direction will move block 62 away from block 58. A variable normal positioning of the jaw is thus made possible.

A jaw block 81 exactly like block 62 is mounted on bar 56 adjacent block 59 and has engaged therewith the threaded end of a shaft 82 which is journaled in block 59 coaxially with shaft 61 and is provided with an abutment collar 83 and with a knob 84. It will be evident that by turning the knob 84 appropriately the jaw block can be given a normal position in variably spaced relation to block 59.

It will thus be seen that the space S between the jaws 62 and 81, Figure 3, can be adjusted from either or both directions. In the space S is positioned a yoke 85 which straddles bar 56, Figures 3, 5, and 7, and is secured to plate 54, the yoke having a flat horizontal top surface 86 which serves as a guide and support for the strip to be tested. Desirably the yoke is provided with an upstanding stop 87 toward the rear of face 86 as particularly shown in Figure 5.

Plate 54 is provided on a diameter with vertical bores 88 and 89, Figure 4, which are equally spaced from the center of plate 54, the bore 88 being in front of jaw 62 and to the left of the space S while the bore 89 is to the rear of jaw 81 and to the right of the space S. Fixed in the bores 88 and 89 are tubular uprights 90 and 91, these uprights having stop collars 92 and 93 held against the top of the plate 54 by nuts 94 and 95 beneath the latter, Figure 4. Slidable in members 90 and 91 are upright rods 96 and 97 whose lower ends are fixed in plate 38 of assembly 37. Reference numeral 98 designates a cross head above tubular upright 90 and 91 having set therein thimbles 99 and 100 which receive the upper ends of uprights 96 and 97 which are secured thereto by pins 101 and 102. The thimbles have bottom flanges 103 and 104 engaged under shoulders provided in the cross head for the transmission of upward movement to the latter, the thimbles resting on the upper ends of members 90 and 91 for

the support of the cross head and associated parts.

The cross head has secured thereto a bar 105 exactly like bar 56 and parallel thereto and in the axial plane thereof. Fixed to the under side of the cross head are blocks 106 and 107 in which are slidably journaled shafts 108 and 109 which are exactly the same as shafts 61 and 82 and engage jaw block 110 and 111 which are the same as blocks 62 and 81. Shaft 108 is swiveled to the piston rod of unit C' and shaft 109 is provided with an adjusting knob 109'.

Block 106 has outwardly extending arms 112 and 113 which carry a cylinder and piston unit C' like the unit C but positioned inwardly thereof so as not to interfere. In the space between jaws 110 and 111 a yoke 115, which is exactly like yoke 85, straddles bar 105, the yoke having a guide face 116 directly above and parallel to the face 86 of yoke 85 and having a stop 117 aligned with stop 87.

In Figures 1 and 2 reference numeral 118 designates a pipe leading from a source of air under pressure to a rotary three-way valve 119, the latter having a connection 120 to a fitting 121 in the head 67, a flexible hose 122 leading from the fitting 121 to a fitting 123 in the outer head of unit 114.

The stem of valve 33 has secured thereto an operating handle 124, Figures 1 and 2 which has an extension 125 pivoted to one end of a link 126 whose other end is pivoted to an arm 127 on the stem of valve 119, arm 127 having the same effective length as arm 125. By swinging arm 124 a certain distance to the right water under pressure will be admitted beneath piston 22 and air under pressure will be simultaneously admitted to the pneumatic cylinders. Further movement of arm 124 to the right will connect pipe 32 to the outlet 128 of valve 33 while the pneumatic cylinders will be simultaneously vented to the outlet 129 of valve 119. Breathing at the right end sides of the pneumatic pistons, for the prevention of dash pot effects can be provided for in any suitable manner, for example, by aperturing the right hand cylinder heads.

For the purpose of illustration it is assumed that a strip of plywood P, Figures 3 and 7, is to be tested for the strength of the glue line. The strip is cut to a length so that it can be freely slid in upright position between the guide faces of the yokes 85 and 115 and against the stops 87 and 117, the strip usually being about an inch in width. The strip P is shown as having three plies and as having been oppositely kerfed through the outer plies, the kerfs being a certain distance apart and out of the gripping area of the jaws. As shown in Figure 7, jaws 81 and 111 having been adjusted to contact with the adjacent face 60 of the strip and a straight edge member 130, secured to jaw 111, is aligned with the vertical rear edge of jaw 81, showing that the jaws have been uniformly adjusted. A similar straight edge member can be associated with the other jaws, 65 if desired, although the accuracy of their adjustment is not of great importance and for ordinary purposes their normal position may always be that shown in Figure 3.

When valves 33 and 119 are now simultaneously turned to their supply position, water and air will be simultaneously applied but due to the rapid pneumatic action, jaws 62 and 110 will be displaced to engage the strip, as shown in Figure 7, before pressure has had time to build up substantially in the hydraulic chamber. As the water

pressure builds up, piston 22 will rise and bearing against diaphragm 40 will carry with it the cross-head and upper jaws until the tension on the strip becomes such that the strip separates. The pressure at which the strip separates is indicated by the gauge needle and noted by the operator. The valves are now turned to their second, or exhaust position, and all of the pistons are returned, those of the pneumatic units by the springs and that of the hydraulic unit by gravity.

In Figure 3 there are shown fingers 131 and 132 projecting radially from piston 22 and assembly 37, these giving a direct visual indication of the relative position of the two elements.

A lubricating system for the jaws has been shown in Figure 3 and is believed to be clear without explanation. Elements as at 133 are oil hole plugs.

As has been previously stated, the disclosure herein is intended as illustrative and not restrictive of the invention, and variations in the form and arrangement of parts are contemplated under the claims which follow:

We claim:

1. In apparatus for testing the tensile strength of a strip of material, two sets of opposed cooperating jaws, one jaw of each set being reciprocable relative to its cooperating jaw, the jaws of each set being normally spaced apart to provide an opening between them greater than the thickness of the strip to be tested and said sets being arranged so that the jaw openings are in alignment, an independent fluid pressure actuated device associated with each of said reciprocable jaws for moving each toward its cooperating jaw to clamp longitudinally spaced portions of the strip when the strip is disposed in the jaw openings, a three way valve arranged for the simultaneous supply of pressure fluid to the fluid pressure actuated devices and for the simultaneous exhaust therefrom, and means for moving the said sets of jaws apart whereby to tension the clamped strip.

2. In apparatus for testing the tensile strength of a strip of material, two sets of opposed cooperating jaws, one jaw of each set being reciprocable relative to its cooperating jaw, the jaws of each set being normally spaced apart to provide an opening between them greater than the thickness of the strip to be tested and said sets being arranged so that the jaw openings are in alignment, pneumatically actuated means associated with said reciprocable jaws for moving them toward the respective cooperating jaws to clamp longitudinally spaced portions of the strip when the strip is disposed in the jaw openings, valve means for controlling the air pressure supply, hydraulically actuated means for moving the said sets of jaws apart whereby to tension the clamped strip, valve means for controlling the water pressure supply, and means for simultaneously operating the two valve means for simultaneous supply.

3. In apparatus for testing the tensile strength of a strip of material, two sets of opposed cooperating jaws, one jaw of each set being reciprocable relative to its cooperating jaw, the jaws of each set being normally spaced apart to provide an opening between them greater than the thickness of the strip to be tested and said sets being arranged so that the jaw openings are in alignment, an independent pneumatically actuated device associated with each of said reciprocable jaws for moving each toward its cooperating jaw to clamp longitudinally spaced portions of the

strip when the strip is disposed in the jaw openings, valve means controlling the air pressure for the simultaneous supply to the pneumatically actuated devices, hydraulically actuated means for moving the said sets of jaws apart whereby to tension the clamped strip, valve means for controlling the water pressure supply, and means for simultaneously operating the two valve means for the simultaneous supply of air and water.

10 4. In apparatus for testing the tensile strength of a strip of material, two sets of opposed cooperating jaws, one jaw of each set being reciprocable relative to its cooperating jaw, the jaws of each set being normally spaced apart to provide an opening between them greater than the thickness of the strip to be tested and said sets being arranged so that the jaw openings are in alignment, an independent pneumatically actuated device associated with each of said reciprocable jaws for moving each toward its cooperating jaw to clamp longitudinally spaced portions of the strip when the strip is disposed in the jaw openings, a three way valve arranged for the simultaneous supply of air pressure to the pneumatically actuated devices and for the simultaneous exhaust therefrom, hydraulically actuated means for moving the said sets of jaws apart whereby to tension the clamped strips a three way valve for controlling the supply of water pressure to said hydraulically actuated means and the exhaust therefrom, and means for simultaneously operating said valves for simultaneous exhaust.

20 5. In apparatus for testing the tensile strength of a strip of material, a pair of gripping devices arranged to grip longitudinally spaced portions of a strip to be tested, an independent pneumatically actuated device associated with each of said gripping devices and operable to close the latter on the strip, hydraulically actuated means arranged to move said gripping devices apart to tension the gripped strip, a common valve for controlling the simultaneous supply of air to the pneumatically actuated devices, a valve for controlling the supply of water to said hydraulically actuated means, and a common operating means for operating said valves in unison.

30 6. In apparatus for testing the tensile strength of a strip of material, a pair of gripping devices arranged to grip longitudinally spaced portions of a strip to be tested, an independent pneumatically actuated device associated with each of said gripping devices and operable to close the latter on the strip, hydraulically actuated means arranged to move said gripping devices apart to tension the gripped strip, a common three-way valve for controlling the simultaneous supply of air to the pneumatically actuated devices and for controlling the simultaneous exhaust therefrom, a three-way valve for controlling the supply of water to the hydraulically actuated means and for controlling the exhaust therefrom, and a common operating means for operating said valves in unison.

40 7. In apparatus for testing the tensile strength of a strip of material, a base, a pair of horizontally opposed jaws on said base, means retaining said jaws against upward displacement relative to the base, one of said jaws being reciprocable relative to the other and being normally spaced from said other to provide an opening between them greater than the width of the strip to be tested, a cylinder and piston unit supported by said base, the piston of said unit being operatively associated with said reciprocable jaw, a pair of upright members supported by said base

for vertical reciprocation, said members being disposed at opposite sides of said jaw opening, a crosshead fixed to said members above said jaws, a pair of horizontally opposed jaws beneath said crosshead, means retaining the second-mentioned pair of jaws against downward displacement relative to the crosshead, said second-mentioned pair of jaws normally defining an opening of the same extent as the first opening and aligned therewith and one thereof being reciprocable relative to the other, a cylinder and piston unit carried by the crosshead of which the piston is operatively associated with the reciprocable jaw of said second-mentioned pair, means for supplying a pressure fluid to said units whereby to move each reciprocable jaw toward its associated jaw to clamp longitudinally spaced portions of the strip when the strip is disposed in the jaw openings, a common valve for controlling the supply of pressure fluid to both of said units, and means for moving said upright members upwardly whereby to tension the clamped strip.

8. In apparatus for testing the tensile strength of a strip of material, a base, a pair of horizontally opposed jaws on said base, means retaining said jaws against upward displacement relative to the base, one of said jaws being reciprocable relative to the other and being normally spaced from said other to provide an opening between them greater than the width of the strip to be tested, a cylinder and piston unit supported by said base, the piston of said unit being operatively associated with said reciprocable jaw, a pair of upright members supported by said base for vertical reciprocation, said members being disposed at opposite sides of said jaw opening, a crosshead fixed to said members above said jaws, a pair of horizontally opposed jaws beneath said crosshead, means retaining the second-mentioned pair of jaws against downward displacement relative to the crosshead, said second-mentioned pair of jaws normally defining an opening of the same extent as the first opening and aligned therewith and one thereof being reciprocable relative to the other, a cylinder and piston unit carried by the crosshead of which the piston is operatively associated with the reciprocable jaw of said second-mentioned pair, means for supplying pressure fluid to said units whereby to move each reciprocable jaw toward its associated jaw to clamp longitudinally spaced portions of the strip when the strip is disposed in the jaw openings, a common three way valve for controlling the supply and exhaust of pressure fluid to and from each of said units simultaneously, and means for mov-

ing said upright members upwardly whereby to tension the clamped strip.

9. In apparatus for testing the tensile strength of a strip of material, a base, a pair of horizontally opposed jaws on said base, means retaining said jaws against upward displacement relative to the base, one of said jaws being reciprocable relative to the other and being normally spaced from said other to provide an opening between them greater than the width of the strip to be tested, a cylinder and piston unit supported by said base, the piston of said unit being operatively associated with said reciprocable jaw, a pair of upright members supported by said base for vertical reciprocation, said members being disposed at opposite sides of said jaw opening, a crosshead fixed to said members above said jaws, a pair of horizontally opposed jaws beneath said crosshead, means retaining the second-mentioned pair of jaws against downward displacement relative to the base, one of said jaws being reciprocable relative to the other and being normally spaced from said other to provide an opening between them greater than the width of the strip to be tested, a cylinder and piston unit supported by said base, the piston of said unit being operatively associated with said reciprocable jaw, a pair of upright members supported by said base for vertical reciprocation, said members being disposed at opposite sides of said jaw opening, a crosshead fixed to said members above said jaws, a pair of horizontally opposed jaws beneath said crosshead, means retaining the second-mentioned pair of jaws against downward displacement relative to the crosshead, said second-mentioned pair of jaws normally defining an opening of the same extent as the first opening and aligned therewith and one thereof being reciprocable relative to the other, a cylinder and piston unit carried by the crosshead of which the piston is operatively associated with the reciprocable jaw of said second-mentioned pair, means for supplying pneumatic pressure fluid to said units whereby to move each reciprocable jaw toward its associated jaw to clamp longitudinally spaced portions of the strip when the strip is disposed in the jaw openings, hydraulic pressure fluid responsive means for moving said upright members upwardly whereby to tension the clamped strip, separate valve means for the control of the two pressure fluids, and a common operator for said valve means so that air and water under pressure can be simultaneously supplied to said units and hydraulic pressure fluid responsive means respectively.

WALTER D. LAWSHE.
